UNITED STATES PATENT OFFICE.

WILLIAM T. ESTBERG, OF PHILADELPHIA, PENNSYLVANIA, ASSIGNOR TO PENN
PRESSED METAL CO., OF PHILADELPHIA, PENNSYLVANIA, A CORPORATION OF
NEW JERSEY.

OIL-CUP.

1,119,145.

Specification of Letters Patent.

Patented Dec. 1, 1914.

Application filed December 16, 1913. Serial No. 806,955.

To all whom it may concern:

Be it known that I, WILLIAM T. ESTBERG, a citizen of the United States, residing at Philadelphia, in the county of Philadelphia and State of Pennsylvania, have invented 5 certain new and useful Improvements in Oil-Cups, of which the following is a specification.

The object of my invention is to provide 10 an oil cup of novel, simple and efficient construction having a removable cap closing the top thereof and provided with means to hold it in place; and having an opening in the body portion of the cup through which 15 oil may be supplied in filling the cup, and a movable door closing said opening.

The invention includes a novel means for 20 clearing dirt from the filling opening and preventing the dirt from entering the cup, 25 a novel means for holding the cup in place and permitting it to be readily applied to or removed from the body portion, a novel construction and arrangement of parts whereby a single spring performs the double 30 function of holding the door closed and the cap retaining means in operative position, and various novel features of construction and combinations of parts hereinafter fully described and particularly claimed.

35 In the accompanying drawings, illustrating my invention, Figure 1, is a perspective view of my improved oil cup. Fig. 2, is a vertical section thereof, taken through cap retaining lugs. Fig. 3, is a vertical section thereof, taken through the filling openings. Fig. 4, is a side view of the upper portion of 40 the cup with one of the cap retaining lugs in the foreground. Fig. 5, is a side view of the upper portion of the cup with one of the filling openings in the foreground. Fig. 6, is a horizontal section through the cup, on line 6-6 of Fig. 4.

45 Referring to the drawings, 2 designates the hollow body portion of the cup adapted to contain the oil. The upper end of the body portion is made cylindrical in form although, generally speaking, the body portion may be of any shape and size for its intended purpose. Its lower end terminates 50 in a screw-threaded nipple 3 which is adapted to be screwed into the piece of machinery or other device to be supplied with oil, the nipple 3 being provided with a suitable discharge opening 4 through which oil may

pass from the cup to the part being lubricated. 55

The upper end of the body portion 2 is closed by a cap 5 having a smooth bottom face fitted against a corresponding smooth upper face of the body portion in a manner 60 to prevent dirt from entering the cup and to permit the cap 5 to be turned about the axis of the cup. Opposite sides of the cap 5 are provided with downwardly-extending lugs 7 having their inner faces slidably 65 fitted to the outer face of the cylindrical upper end of the body portion 2 and adapted to assist in holding the cap 5 centrally upon the body portion 2 and to permit it to turn thereon. Each lug 7 has a horizontal slot 8 70 therein to receive a pin 9 projecting from the body portion 2. The slot 8 in each lug 7 is open at one end to permit the pin 9 to leave the slot when the cap 5 is turned in one direction, and the slot is closed at the 75 opposite end so that its end wall will form a stop to limit the movement of the cap 5 when it is turned in the reverse direction. The slots 8 in the two lugs 7 are so arranged with respect to each other that when the 80 cap is turned in one direction the slots 8 will leave the pins 9, and when the cap 5 is turned in the reverse direction, the slots 8 will receive the pins 9. When the pins 9 are within the slots 8, the cap 5 is thereby held 85 down upon the body portion 2 and when the pins 9 are out of the slots 8, the cap 5 may be readily removed from the body portion 2.

Opposite sides of the top of the body portion 2 are provided with filling openings 10 90 to receive the discharge end of an oil can spout in filling the cup with oil. These openings 10 are normally closed by doors 11 forming downwardly-extending flanges on a horizontal plate or member 12 located 95 within the cup. This member 12 is pivoted on a centrally-arranged vertical pin 13 extending downwardly from the cap 5, the plate or member 12 being adapted to turn about the axis of the pin 13 and to slide 100 against the bottom face of the cap 5. Each door 11 is fitted to slide against the inner, annular face of the body portion 2, and each door 11 is provided with a projection 14 extending through its opening 10 and outwardly beyond the outer face of the body portion 2. The doors 11 and projections 14 are so arranged with respect to each other 105

and to the openings 10, that when the member 12 is turned in one direction, the doors 11 will close the openings 10 and the projections 14 will engage opposite walls 15 of the openings 10 and limit the movement of the doors 11, and that when the member 12 is turned in the reverse direction, the doors 11 will clear the openings 10 and the projections 14 will engage the other opposite walls 16 of the openings 10 and limit the movement of the doors 11.

The doors 11 are maintained normally and yieldingly closed with their projections 14 in engagement with the walls 15 by the action of a spring 17 located within a cavity in the bottom of the cap 5 and encircling the pivot pin 13 and having one end engaged with the cap 5 and the other end engaged with the member 12. This spring 20 also tends to rotate the cap 5 in the direction of the arrow in Fig. 1 and thereby maintain the walls of the closed ends of the slots 8 in engagement with the pins 9 to prevent accidental disengagement of the lugs 7 from 25 the pins and the consequent liability of displacement of the cap 5.

When the cap 5 is removed from the body 2, the lugs 7 are engaged by the projections 14 and thus limit the movement thereof under the influence of the spring 17. With the parts in this position, the cap may be readily applied to the body 2 by first inserting the lower portions of the projections 14 into the upper portions of the openings 10, then turning the head 5 in a direction opposite to the arrow in Fig. 1 until the lugs 7 can be lowered to bring the pins 9 into position to enter the open ends of the slots 8 and then lowering the cap 5 to the top of 40 the body 2 and turning or permitting the spring 17 to turn the cap 5 to bring the walls of the closed ends of the slots 8 into engagement with the pins 9. By the reversal of this operation, the cap 5 may be 45 readily removed from the body 2.

When the parts are in the position shown and it is desired to fill the cup with oil, it is merely necessary to engage the discharge end of an oil can spout with one of the projections 14 and thereby move back its door 11 to clear its opening 10 and then project the spout through the opening 10 and into the cup. Upon the withdrawal of the spout the spring 17 will return the parts to the 55 position shown and close the openings 10.

The walls 16 of the openings 10 toward which the projections 14 are moved when the doors 11 are opened, are provided with knife edges against which the doors slide, as 60 clearly shown in Fig. 6. It will, therefore, be readily understood that each time the projections 14 are moved toward the walls 16, the knife edges will serve to clear the openings 10 of any dirt, that may collect 65 therein between the projections 14 and walls

16, and that the dirt will be prevented from entering the cup.

I claim:

1. In an oil cup, the combination of a cylindrical body portion adapted to contain the oil, a removable cap rotatable on and closing the top of said body portion, a lug extending downwardly from said cap and having a slot therein open at one end and closed at the other end, a pin projecting from said body portion and into said slot, said pin and said lug preventing upward displacement of said cap, and a spring tending to rotate said cap and maintain the wall of the closed end of said slot in engagement with said pin. 75

2. In an oil cup, the combination of a cylindrical body portion adapted to contain the oil and having a filling opening in a side wall thereof, a movable door adjacent to said opening and the inside wall of said body portion and movable into and from a position closing said opening, a removable cap closing the top of said body portion, a spring holding said door yieldingly in the closed position, lugs extending downwardly from said cap and engaging parts on said body portion and preventing upward displacement of said cap. 85

3. In an oil cup, the combination of a body portion adapted to contain the oil and having a filling opening in a side wall thereof, a movable door adjacent said opening and adapted to close the same, a removable cap closing the top of said body portion, 100 said cap having a locking part coöoperating with a part on said body portion and holding said cap in place, and a spring holding said door normally in the closed position and holding said locking part normally in engagement with its coöoperating part on the body portion. 95

4. In an oil cup, the combination of a cylindrical body portion adapted to contain the oil and having a filling opening in a side wall thereof, a removable cap closing the top of said body portion, a member carried by said cap and pivoted thereto centrally thereof, a door carried by said pivoted member and adapted to close said opening, and a spring holding said door yieldingly in the closed position. 110

5. In an oil cup, the combination of a cylindrical body portion adapted to contain the oil and having a filling opening in a side wall thereof, a removable cap closing the top of said body portion, a member carried by said cap and pivoted thereto centrally thereof, a door carried by said pivoted member and adapted to close said opening, said 120 cap having a locking part coöoperating with a part on said body portion and holding said cap in place, and a spring holding said door normally in the closed position and holding said locking part normally in engagement 125 130

with its coöperating part on the body portion.

6. In an oil cup, the combination of a cylindrical body portion adapted to contain the oil and having a filling opening in a side wall thereof, a removable cap closing the top of said body portion, a member carried by said cap and pivoted thereto centrally thereof, a door carried by said pivoted member and adapted to close said opening, a lug extending downwardly from said cap and having a slot therein open at one end and closed at the other end, a pin projecting from said body portion and into said slot, said pin and said lug preventing upward displacement of said cap, and a spring holding said door normally in the closed position and holding the wall of the closed end of said slot normally in engagement with said pin.

7. In an oil cup, the combination of a body portion adapted to contain the oil and having a filling opening in the top of a side wall thereof, a removable cap closing the top of said body portion, a movable door adjacent said opening and adapted to close the same and having a part adapted to engage a wall of the body portion when the door is in the closed position and to slide vertically in engagement therewith when the cap is applied to the body portion, said cap having a downwardly-extending lug, said body portion having a part adapted to coöperate with said lug to hold said cap in place, and a spring pressing said door normally toward its closed position and pressing said lug normally into engagement with said part.

8. In an oil cup, the combination of a cylindrical body portion adapted to contain the oil and having a filling opening in the top of a side wall thereof, a removable cap closing the top of said body portion, a member carried by said cap and pivoted thereto centrally thereof, a door carried by said pivoted member and adapted to close said opening, said door having an outwardly-extending projection adapted to engage a wall of the body portion when the door is in the closed position and to slide vertically in engagement therewith when the cap is applied to the body portion, said cap having a downwardly-extending lug, said body portion having a part adapted to coöperate with said lug to hold said cap in place, and

a spring pressing said door normally toward its closed position and pressing said lug normally into engagement with said part.

9. In an oil cup, the combination of a cylindrical body portion adapted to contain the oil and having a filling opening in the top of a side wall thereof, a removable cap closing the top of said body portion, a member carried by said cap and pivoted thereto centrally thereof, a door carried by said pivoted member and adapted to close said opening, said door having an outwardly-extending projection adapted to engage a wall of the body portion when the door is in the closed position and to slide vertically in engagement therewith when the cap is applied to the body portion, a lug extending downwardly from said cap and having a slot therein open at one end and closed at the other end, a pin projecting from said body portion and into said slot, said pin and said lug preventing upward displacement of said cap, and a spring pressing said door normally toward its closed position and pressing the wall of the closed end of said slot normally toward said pin.

10. In an oil cup, the combination of a body portion adapted to contain the oil and having a filling opening in a wall thereof, and a movable door adjacent said opening and adapted to close the same and having an outwardly extending projection adapted to lie adjacent one side wall of said opening when the door is closed, the opposite side wall of said opening having a knife-edge formed thereon adjacent to which the outer face of the door moves when opened.

11. In an oil cup, the combination of a body portion adapted to contain the oil and having a filling opening in a wall thereof, said body portion having a cap provided with a projecting pin, a door carried by a cap mounted on and movable about the axis of said pin, said door being movable to a position closing said opening, and a spring encircling said pin and maintaining said door yieldingly in the closed position.

In testimony whereof I affix my signature in presence of two witnesses.

WILLIAM T. ESTBERG.
